Fig. 3

Fig. 4

FIGURE 1 is a perspective view of the table in expanded position with leaves of the table inserted and showing my new design;

FIGURE 2 is a perspective view of the table with leaves omitted and disclosing the table in a contracted condition;

FIGURE 3 is a side elevational view of the table of FIGURE 2, viewing the same from the right side thereof; and

FIGURE 4 is a side elevational view of the table of FIGURE 2, viewing the same from the front thereof.

The dominant features of my design reside in those portions shown in full lines on the drawing.

I claim:

The ornamental design for an expandable table, substantially as shown and described.
